UNITED STATES PATENT OFFICE.

JOHN A. HOFF, OF CINCINNATI, OHIO.

TESTING DEVICE.

1,211,942.

Specification of Letters Patent.

Patented Jan. 9, 1917.

Application filed November 22, 1915. Serial No. 62,789.

To all whom it may concern:

Be it known that I, JOHN A. HOFF, a citizen of the United States, residing at Cincinnati, in the county of Hamilton and State 5 of Ohio, have invented certain new and useful Improvements in Testing Devices, of which the following is a specification.

My invention relates to testing devices, and is intended for employment for testing 10 the pressures in bottles containing charged beverages, for instance, soda and mineral waters, Coca Cola, and other potable fluids.

The flavor and durability of the beverage depends largely upon the existence and the 15 maintenance of pressure in and upon the potable fluid, the absence of the pressure being evidenced by what is known as a "flat" taste. The pressure is usually supplied by a charge of carbonic acid gas, a pressure of 20 approximately three atmospheres being a usual pressure applied to the contents of the bottle, this pressure being instanced as an example and not as a limitation. Disputes often arise between the manufacturer of the 25 charged beverage and the retailer as to whether the bottles contain sufficient pressure. The appearance and taste of the beverage are not always criterions as to the amount of pressure in the bottle and are at 30 best matters of opinion of the individual.

It is the object of my invention to provide a device whereby the pressure in the inside of the bottle may be accurately determined, and further to provide a novel testing device 35 which may be readily applied to any bottle, for instance, of a given lot of bottles, and the pressure therein indicated upon a pressure-gage for definitely determining the pressure.

40 The invention will be further readily understood from the following description and claims, and from the drawing, in which latter:

Figure 1 is a side elevation of my improved device, showing the same applied to a bottle, the latter partly broken away. Fig. 2 is a plan view of my improved device. Fig. 3 is a side elevation of the same, partly shown in axial section on the line 3—3 of 45 Fig. 2, with the piercing-stem withdrawn. Fig. 4 is an axial section of the attaching and piercing portion of my improved device, taken on the line 3—3 of Fig. 2, showing the piercing-stem in pierced relation. Fig. 5 is a detail in side elevation, showing 50 the catch for the keeper of the metal cap;

and, Fig. 6 is a cross-sectional detail, taken on the line 6—6 of Fig. 4.

My improved device comprises a casing 11, on which there is a housing 12, shown 60 movable with relation to the casing by having threaded engagement 13 with the shank 14 of the casing. The housing is provided with lips 15 arranged to be received over the edge 16 of a usual metal cap 17, instanced as a usual crown seal received over the mouth 18 of a bottle 19.

A seal is provided for surrounding a portion of the cap, instanced as a compressible washer 21, for instance of rubber, arranged 70 to be clamped upon the top of the cap, the washer being provided with an aperture 22 through which a piercing-stem 23 is arranged to be received. The washer is instanced as being provided with an inner 75 metal ring 24 and an outer metal ring 25, so as to confine the washer laterally. The washer is located in a recess 28 in the housing. The shank 14 is provided with an annular projection 29 which coacts with the 80 washer for pressing the washer against the crown 30 of the metal cap for surrounding a portion of the crown intended to be pierced.

The capped end of the bottle is adapted to be placed within the housing by lateral 85 movement between the mouth of the bottle and the housing, for placing the lips 15 over the edge of the cap. Relative rotation between the housing and casing causes a clamping of the washer upon the cap. 90

If desired, the cap may be held in the housing, as by means of a keeper comprising a rock-shaft 32 rockable in a bearing 33 of the housing, and provided with a head 34 eccentrically placed on the rock-shaft arranged to be shifted so as to be received over the edge of the cap. The normal position of the head 34 is adjacent to the base of the housing, with the head turned outwardly, the head being provided with an inclined 100 face 35 normally presented inwardly. The head is arranged to be held in normal position by means of a pin 36 received in an annular groove 37 in the rock-shaft, the pin being received through the wall of the 105 bearing 33 and pressed toward the rock-shaft by means of being mounted on a spring 38 secured to the housing by a screw 39, the spring being provided with an out-turned end 40 arranged to be readily engaged for moving the pin 36 out of range with the annular groove 37.

When the cap has been received between the lips 15, the keeper is arranged to be moved axially and to be rotated, as by means of a handle 41, for placing the head 34 thereof across the edge of the cap. When in such position the pin 36 may be received in an annular groove 42 in the rock-shaft.

The piercing-stem 23 extends through a hole 45 in the casing, shown as extending lengthwise of the shank 14. A passage or 10 passages 46 extend lengthwise of the piercing-stem, being shown formed by forming the piercing-stem as a flat stem, the lengthwise passages being between the piercing-stem and the wall of the hole through which 15 the stem passes.

The piercing-stem is provided with a piercing-point 47 arranged to pierce the metal cap and the lining 48 thereof, so as to 20 open communication between the inside of the bottle desired to be tested and the passages 46.

The piercing-stem is shown threaded at 25 51, having threaded engagement with a threaded bearing 52 in the casing. It is provided with an operating handle 53. A gasket 55 is in a socket 56 of the bearing 52 and is arranged to be compressed by a gland 57 about the piercing-stem, as by means of a 30 nut 58 having threaded engagement with the casing. The piercing-stem is provided with grooves 59 communicating with the passages 46 and the cavity 60 of the casing.

A suitable pressure-gage 61 is secured to 35 the casing, as by means of the threaded connection 62, there being a pressure-passage 63 communicating by means of the cavity 60 with the pressure-passages 46, so as to indicate upon the dial 64 of the pressure-gage, 40 by means of the pointer 65 thereof, the pressure there is in the bottle, this pressure being communicated to the pressure-gage through the pierced hole in the cap of the bottle, the passages 46, cavity 60 and passage 45 63, the escape of pressure being prevented by the compression of the compressible washer 21 against the crown of the cap by means of the annular projection 29 surrounding the pierced portion of the crown. 50 If desired, the pressure may be released by means of the valve 66. When the pressure has been read the testing device may be removed from the bottle.

Having thus fully described my invention, what I claim as new and desire to secure by Letters Patent, is:

1. In a testing device of the character described, the combination of a clamp arranged to be clamped to the cap of a metal-capped bottle, said clamp comprising a 60 packing surrounding a portion of said cap to be pierced and pressed against said cap, a piercing-stem, means for forcing said piercing-stem toward said cap for piercing 65 said surrounded portion of said cap, and

a pressure-gage, said device provided with a passage communicating with said pressure-gage and said pierced part of said cap for indicating the pressure in said bottle on said pressure-gage.

70

2. In a testing device of the character described, the combination of a clamp arranged to be clamped to the cap of a metal-capped bottle, said clamp comprising a packing surrounding a portion of said metal-cap to be pierced and pressed against said cap, a piercing-stem, means for forcing said piercing-stem toward said cap for piercing said surrounded portion of said cap, a pressure-gage, said device provided 80 with a passage communicating with said pressure-gage and said pierced part of said cap for indicating the pressure in said bottle on said pressure-gage, and a valve communicating with said passage for releasing 85 the pressure in said bottle.

3. In a testing device of the character described, the combination of a casing, a housing arranged to be received about the cap of a metal-capped bottle, a washer in said 90 housing provided with an aperture, means between said casing and housing for clamping said washer to said cap, a piercing-stem having threaded connection with said casing for moving said stem through said aperture and piercing said cap, and a pressure-gage, there being a pressure-passage lengthwise of said stem communicating with said pressure-gage.

4. In a testing device of the character described, the combination of a casing, a housing arranged to be received by lateral movement about the cap of a metal-capped bottle, a keeper coacting with said housing for securing said housing to said cap, said casing comprising a shank threaded in said housing, a compressible washer pressed between said shank and said cap by relative rotation between said housing and shank, said shank and washer having apertures 110 therein in line with each other, a piercing-stem in said aperture in said shank, said piercing-stem having threaded connection with said casing arranged to move said piercing-stem through said aperture in said washer for piercing said cap, and a pressure-gage, there being a pressure-passage 115 extending lengthwise of said stem communicating with said pressure-gage.

5. In a testing device of the character described, the combination of a casing, a housing arranged to be received by lateral movement about the cap of a metal-capped bottle, a keeper coacting with said housing for securing said housing to said cap, said casing comprising a shank threaded in said housing, a compressible washer pressed between said shank and said cap by relative rotation between said housing and shank, said shank and washer having apertures 125 130

therein in line with each other, a piercing-
stem in said aperture in said shank, said
piercing-stem having threaded connection
with said casing arranged to move said
piercing-stem through said aperture in said
washer for piercing said cap, a pressure-
gage, there being a pressure-passage extending
lengthwise of said stem communicating
with said pressure-gage, and a valve com-
municating with said pressure-passage for
releasing the pressure in said bottle and said
pressure-gage.

6. In a testing device of the character
described, the combination of a casing, a
15 housing arranged to be received by lateral
movement about the cap of a metal-capped
bottle, a keeper, said keeper comprising an
axially movable and rockable shaft jour-
naled in said housing, and a head arranged

to be placed across the edge of said cap for 20
holding said cap in said housing, a catch
for retaining said keeper in retracted posi-
tion, a washer in said housing, said casing
provided with a shank, means for pressing
said washer between said shank and said 25
cap, a piercing-stem having threaded con-
nection with said casing for forcing said
stem past said washer through said cap, and
a pressure-gage, there being a passage
lengthwise of said piercing-stem communi- 30
cating with said pressure-gage.

In testimony whereof, I have hereunto
signed my name in the presence of two sub-
scribing witnesses.

JOHN A. HOFF.
